UNITED STATES PATENT OFFICE.

LEON S. MICHALSKI, OF BUFFALO, NEW YORK, ASSIGNOR OF ONE-HALF TO JOSEPH J. MICHALSKI, OF BUFFALO, NEW YORK.

DESIGN FOR CANDY.

Application filed April 5, 1922. Serial No. 1,547. Term of patent 14 years.

To all whom it may concern:

Be it known that I, LEON S. MICHALSKI, a citizen of Austria, residing at Buffalo, in the county of Erie and State of New York, have invented a new, original, and ornamental Design for candy, of which the following is a specification, reference being had to the accompanying drawing, forming part thereof.

The figure is a perspective view of the candy, showing my new design.

I claim:

The ornamental design for candy, as shown.

LEON S. MICHALSKI.
